FEED MECHANISM FOR STOKERS

John Wynn, Jr., Canton, Ohio

Application April 7, 1931, Serial No. 528,305

5 Claims. (Cl. 221—138)

The invention relates to mechanical stokers and more particularly to the mechanism for agitating, sizing and feeding coal from a bin, or the like, to a conveyer of a mechanical stoker 5 of the general type disclosed in my prior application Serial No. 507,095.

An object of the improvement is to provide a rotatable, perforated disk in the lower portion of a coal bin or the like for agitating the coal 10 and feeding coal of proper size to a conveyer leading to the furnace.

Another object is to provide a stationary banking bar arranged to cooperate with the rotatable disk to hold a portion of the coal 15 against movement with the disk in order to more effectually feed the coal through the perforations in the disk.

A further object is to provide a stationary shearing bar beneath the rotatable disk for the 20 purpose of cutting or breaking large lumps of coal which may pass partially through the openings in the disk, thus properly sizing the coal for use in the stoker.

A still further object is to provide a wiper lug 25 or stud, preferably upon the banking bar, for breaking the upper portions of large lumps of coal which may pass partially through the openings in the disk, or for removing such large lumps of coal from the openings.

Still another object is to provide an agitator bar extending beyond the peripheral portion of the rotating disk, for agitating the coal around the periphery of the disk and assisting the same to be fed onto the disk.

Another object of the improvement is to provide a mutilated gear drive for intermittently rotating the perforated disk, whereby the jarring due to repeated starting and stopping of the movement of the disk greatly increases the feeding of the coal through the perforations thereof.

Still another object is to provide such an apparatus in which the feed screw has a greater pitch beyond the perforated disk so as to carry the coal away from the vicinity of the disk at 45 a rapid rate in order to prevent clogging of the conveyer screw with coal adjacent to the disk.

Other objects are to improve and simplify the mechanical structure and driving means for the improved feeding, sizing and agitating mechanism.

The above and other objects which will be later referred to, or which will appear in the accompanying drawings, or the following description, may be attained by constructing the 55 improved, feeding, sizing and agitating mecha-

nism in the manner illustrated in the drawings forming a part hereof, in which

Figure 1 is a plan view of the improved mechanism, parts being broken away for the purpose of illustration;

Fig. 2, a section on the line 2—2, Fig. 1, taken longitudinally of the feed screw;

Fig. 3, a section on the line 3—3, Fig. 1, taken transversely of the feed screw; and

Fig. 4, an elevation of the mutilated gear for 10 intermittently driving the disk.

Similar numerals refer to similar parts throughout the drawings.

The invention contemplates the feeding of fuel in the form of slack, finely divided coal or the like, directly from a coal bin or similar receptacle to a furnace, and for this purpose a conveyer screw 10 extends into the bottom of the coal bin, being located within a tubular housing 11 which communicates with a trough 12 located 15 within the coal bin and receiving the charging 20 end portion of the conveyer screw.

The conveyer screw has a greater pitch within the tubular housing 11, as indicated at 13, than the end portion of the same within the trough, 25 as indicated at 14, for the purpose of rapidly carrying the coal away from the vicinity of the feeding, sizing and agitating mechanism which will be hereinafter described.

The end portion of the conveyer screw is provided with the shaft 15 journaled through the bearing 16 formed in the end wall of the trough 12 and extending through a gear housing 17 formed integral with said trough, the end of 30 said shaft being journaled in a bearing 18 mounted in an opening 19 formed in the outer wall 20 of said gear housing and preferably provided with the peripheral flange 21 through 35 which may be located cap screws 22 for connecting the bearing to the reinforced flange 23 40 formed integral with the wall 20 and surrounding the opening 19.

A bevel pinion 24 is fixed upon the shaft 15 in any suitable manner, such as by the threads 25, being located between the bearings 16 and 18. A ring gear 26 is rotatably mounted above the trough 12 and meshes with the gear 24, for the purpose of rotating said ring gear in a horizontal plane. It should be understood that the feed screw 10 is driven by any suitable means 50 (not shown) and if it is desired to intermittently operate the ring gear 26, the bevel pinion may be mutilated as shown at 24a in Fig. 4, having teeth around only about one-fourth of its periphery, whereby the ring gear 26 will be given 55

only a slight movement with each complete rotation of the bevel pinion.

The ring gear 26 is provided with the peripheral portion 27 which bears upon the horizontally disposed annular flange 28 formed integral with the casting comprising the trough 12 and gear housing 17.

An upright annular flange 29 may be formed at the top of the trough 12 and is adapted to contact with the depending annular flange 30 formed around the inner edge of the ring gear 26. The ring gear thus has bearing upon the annular flanges 28 and 29 upon which it is guided for rotary movement in a horizontal plane.

The disk 31 is mounted upon the ring gear 26, being fixed thereto as by the screws 32, and the central portion of said disk, located above the trough 12, is provided with openings 33 of a diameter not greater than the largest size of coal intended to be fed to the conveyer screw 10, so that the openings 33 act as sizing apertures.

A shearing bar 34 is located diametrically across the under side of the disk 31, being preferably provided with the depending end portions 35 resting upon the lugs 36 formed at the sides of the trough 12, screws 37 being located through said depending portions 35 and into the lugs for rigidly mounting the shearing bar in stationary position.

A post 38 is fixed to the center of the shearing bar 34 and extends upward through the central aperture 39 in the disk 31, a spacing sleeve 40 surrounding said post and being spaced from the central opening 39 of the disk.

A banking bar 41 has its inner end connected to the post 38, as by the aperture 42, resting upon the spacing sleeve 40 and held in fixed contact therewith as by the nut 43 upon the upper screw threaded end of the post 38.

This banking bar is thus spaced above the disk and extends radially to a point beyond the periphery of the disk, being then bent downward substantially at right angles as at 44 and then inward as at 45, preferably terminating in the downturned end 46 which may be secured to the adjacent side wall 47 of the casting forming the trough and gear housing, as by the screw 48. The banking bar is thus held in stationary position and serves to form a stationary bank of coal extending radially across the disk at this point, thus assisting in feeding the coal downward through the apertures 33 in the disk, and into the trough, as the disk rotates.

In order to break the upper portions of any large lumps of coal which become lodged in the apertures 33, or to move the same out of said apertures, to permit smaller coal to pass therethrough, a depending wiper lug or stud 49 may be fixed upon the under side of the banking bar, in line with the centers of the openings 33, and may be provided with the beveled lower end 50 to assist in breaking large lumps of coal.

For the purpose of agitating the coal directly surrounding the disk and in order to cause the same to feed downward onto the surface of the disk, an agitating bar 51 may be fixed to the under side of the disk, as by the screw 52 and extends outward beyond the periphery of the disk, being of suitable length to permit the same to pass the vertical portion 44 of the banking rod.

In the operation of the apparatus the conveyer screw 10 is rotated in the direction of the arrows shown in Figs. 2 and 3, and through the

bevel pinion 24, upon the shaft of the screw, the perforated disk 31 is rotated either continuously during the rotation of the screw, or intermittently, depending upon whether a continuous or mutilated bevel pinion is used.

As the disk is rotated, the coal thereon will be carried around by the disk, some of the finer coal and smaller lumps passing down through the apertures 33 of the disk into the trough 12. The coal being always moved in one direction 10 will bank against the banking bar 41, holding a portion of the coal stationary at this point and causing the same to more rapidly feed down through the openings of the moving disk.

Large lumps of coal which may pass part way 15 through the apertures 33 and become lodged therein will be sheared or broken by the shearing bar 34 as they are brought into contact therewith. Any large lumps of coal which become lodged in the apertures 33 and extend 20 upward therefrom will be crushed or broken by the wiper lug or stud 49 as they are moved into contact therewith or will be dislodged from the apertures and thrown to one side by contact with said wiper lug.

The agitating bar 51 will continuously move 25 through the mass of coal directly surrounding the disk, undermining the same and causing it to flow over the disk.

By providing the mutilated bevel pinion it will 30 be seen that the disk will be intermittently rotated, being started and stopped during each revolution of the feed screw, the jarring due to the constant starting and stopping of the disk further assisting in feeding the coal down 35 through the apertures 33 of the disk and into the feed trough 12. As the coal is fed to the trough 12 it will be conveyed out of the same by the feed screw and due to the greater pitch of the screw as shown at 13, within the tubular 40 housing 11, the coal will be more rapidly fed away from the vicinity of the feeding, sizing and agitating apparatus above described.

As shown in Figs. 2 and 3, the rotatable disk 31 is spaced some distance above the conveyer 45 screw, providing a magazine, above and partly around the screw, which may be filled with coal as the disk rotates. With such a construction it will be evident that in the event the coal is wet, or damp, and may at times bridge across 50 the apertures in the disk, preventing feeding of coal downward through the same, there will be a surplus storage of coal in the magazine which may be delivered by the screw until the apertures in the disk are again cleared, permitting 55 coal to again feed therethrough.

I claim:

1. Fuel feeding mechanism including a trough, a rotatable disk above the trough and having sizing apertures therein, a stationary shearing bar rigidly mounted below the disk for shearing fuel lodged in said apertures, and means for rotating said disk to feed fuel through said apertures into the trough.

2. Fuel feeding mechanism including a trough, a rotatable disk above the trough and having sizing apertures therein, a stationary shearing bar radially located below the disk for shearing fuel lodged in said apertures, and means for rotating said disk to feed fuel through said apertures into the trough.

3. Fuel feeding mechanism including a trough, a rotatable disk above the trough and having apertures therein, a banking bar above the disk, a stationary shearing bar below the disk, and

means for rotating said disk to feed fuel through said apertures into the trough.

4. Fuel feeding mechanism including a trough, a rotatable disk above the trough and having apertures therein, a banking bar above the disk, a wiper lug upon the banking bar and adapted to register with the apertures in the disk, a stationary shearing bar below the disk, and means for rotating the disk to feed fuel through said apertures into the trough.

5. Fuel feeding mechanism including a trough, a rotatable disk above the trough and having apertures therein, a banking bar above the disk, a wiper lug upon the banking bar and adapted to register with the apertures in the disk, an agitating bar fixed to the disk and extending beyond the periphery thereof, and means for rotating the disk to feed fuel through said apertures into the trough.

JOHN WYNN, JR. 10
